US00D907103S

(12) **United States Design Patent** (10) Patent No.: **US D907,103 S**
(45) Date of Patent: ** Jan. 5, 2021

(54) **LASER DESKTOP PROJECTOR**

- (71) Applicant: **Beijing Xiaomi Mobile Software Co., Ltd.**, Beijing (CN)
- (72) Inventors: **Ziran Zhao**, Beijing (CN); **Ningning Li**, Beijing (CN); **Lei Zhang**, Beijing (CN)
- (73) Assignee: **BEIJING XIAOMI MOBILE SOFTWARE CO., LTD.**, Beijing (CN)

(**) Term: **15 Years**

(21) Appl. No.: **35/507,067**

(22) Filed: **Jan. 9, 2019**

(80) **Hague Agreement Data**

Int. Filing Date: **Jan. 9, 2019**
Int. Reg. No.: **DM/200641**
Int. Reg. Date: **Jan. 9, 2019**
Int. Reg. Pub. Date: **Jul. 12, 2019**

(30) **Foreign Application Priority Data**

- Jul. 11, 2018 (CN) 2018 3 0372576
- (51) **LOC (13) Cl.** **16-02**
- (52) **U.S. Cl.**
USPC **D16/230**

(57) **CLAIM**

The ornamental design for a laser desktop projector, as shown and described.

DESCRIPTION

- 1.1: Front view of a laser desktop projector showing our new design.
1.2: Back view thereof.
1.3: Left side view thereof.
1.4: Right side view thereof.
1.5: Top view thereof.
1.6: Bottom view thereof.
1.7: Front, right and top side perspective view thereof.
1.8: Front, right and bottom side perspective view thereof.
